CLAIM

The ornamental design for a shoe upper as shown and described.

DESCRIPTION

FIG. 1 is a perspective view of a shoe upper embodying the new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom perspective view thereof.

The dash-dash broken lines shown in the drawings represent environmental structure of parts of the shoe and portions of the upper, which form no part of the claimed design. The dot-dashed broken lines define the bounds of the claimed design and form no part thereof. The dashed lines shown on the triangular features depict stitching which forms no part of the claimed design.
